Fig. 10.

A technical line drawing of a mechanical part. It features a central horizontal slot with a small circular hole at its left end. On either side of the slot are rectangular flanges. The left flange has a small circular hole near its top edge. The right flange has a vertical slot near its top edge. The entire assembly is labeled with the number '10' above the central slot and '66' to the right of the right flange.

F. S. Stebbins.

UNITED STATES PATENT OFFICE.

FRANK E. STEBBINS, OF WASHINGTON, DISTRICT OF COLUMBIA.

CAR CONSTRUCTION.

No. 897,314.

Specification of Letters Patent.

Patented Sept. 1, 1908.

Application filed December 9, 1895. Serial No. 571,578.

To all whom it may concern:

Be it known that I, FRANK E. STEBBINS, a citizen of the United States, residing at Washington, District of Columbia, have invented certain new and useful Improvements in Car Construction, of which the following, taken in connection with the accompanying drawings, is a specification sufficiently full, clear, and accurate as will enable persons skilled in the art of car-building to physically embody and use the same.

The novelties introduced into the art relate mainly to the reorganization, construction and adaptation of the interior of a car for sleeping purposes.

The main objects are the production of a sleeping car which shall be more convenient, commodious, and open and less obstructed in the top portion thereof than cars heretofore built; which shall have alcoves for use in undressing, dressing and washing adjacent the upper and lower berths; which shall have relatively high windows; which shall have places for storing bedding by day; in which the upper berths may be shut off from the central passage and access thereunto be had from the alcove space, or at the end of the berth; in which the seats shall be adapted to constitute a lounge by day; and which shall be strengthened in the top to prevent crushing in case of accidents.

With these ends and objects to be attained the improvements consist in reorganizing the interior of the car so that alcoves will be formed between or adjacent the sections, each alcove being provided with toilet appliances and means for inclosing the same to constitute a receptacle for bedding by day; in constructing the upper berth so it may contract and fold to a position parallel with the wall and adjacent the plate; in providing the upper berth with a guard on the side next to the central passage and making said berth open at one end to the alcove or open at one end to the central passage; in locating arch rails in the top of the car which shall extend between the plates or between the clear story sills; and in constructing the seats of a section so that one half the area thereof may be transformed into a lounge by day.

The improvements consist still further in certain novelties of construction, formation, and combinations of parts hereinafter set forth and claimed.

The accompanying drawings illustrate one complete example of the physical embodiment of my invention, and one modification of the upper berth, constructed according to the best modes I have so far devised for the practical application of the principles.

Figures 1 and 2 are plan views of two car bodies constituting when united a twin car. Fig. 3 is a cross section of the car taken on line S, S, Fig. 2, and looking in the direction of the arrow, showing one of the upper berths contracted and folded perpendicularly against the wall of the car and adjacent the plate, and the berth on the opposite side of the car lowered and extended in a horizontal plane below the pivots of the berth and in part suspended by the guard at the front edge thereof. Fig. 4 is a cross section of the car on line t—t Fig. 2 looking in the direction of the arrow, showing in part the construction of the alcoves, folding wash basins, and hinged head boards for closing the ends of the sections. Fig. 5 is an enlarged view in sectional elevation taken on line n—n Fig. 2 and showing in one section the upper berth lowered and with the guard in place, and in another section the upper berth closed against the wall of the car, and one alcove closed up as it appears by day. Fig. 6 is a plan view of one section and an alcove adjacent the section showing one location of the bedding when stored, and one half of the seats and backs transformed into a lounge for day use. Fig. 7 is a sectional view of Fig. 6 taken on line m—m. Fig. 8 is a one-half cross section of a car illustrating a modified construction of a contracting upper berth. Fig. 9 is a top plan view of the upper berth panel and movable extension shown in Fig. 3. Fig. 10 is a cross section of Fig. 9. Fig. 11 is an end view of the berth contracted, with one part of the mattress or bed bottom shifted parallel with the other part.

Certain specific elements and parts shown by the drawings which illustrate an application of my method of construction are designated by numerals as follows: 1 are sections consisting of two seats facing each other, the sections being arranged along each side wall of the car as shown; 2, alcoves adjacent the sections; 3, vertical fixed partitions above seat backs; 4, a fixed partition; 54, bulk heads which are in line with the seat backs, one edge of each being in contact with the wall of the car, and extending from the seat backs to the arch rails or roof; 55, seat backs permanently secured in position; 56, head rests secured to the backs; 57, double seat

cushions; 58, removable and adjustable back pieces; 59, grooved plates; 60, journals which fit the grooves in the plates and are carried by the seat cushions; 61, permanent rails of the seat supports; 62, wooden strips secured to the under surfaces of the seat cushions; 63, pins secured to the strips and projecting therefrom; 64, supports upon the seat backs; 65, the lower or inner parts of the upper berths; 66, the upper or outer movable parts of the upper berths; 67, the berth journals or pivot pins by which the upper berth is secured to the wall of the car or to the bulk heads; 5 and 6, the lower and top panels of the inner part of the berth separated by strips of suitable material to form pockets; 7, end pieces; 8, the edge piece of the outer part; 9, parts of wood or metal which telescope between the panels 5 and 6, as shown; 10, end pieces of the outer part; 68, sheathings secured to the roof and which match the edges of the upper berths when closed so as to present a surface continuous with the surface of the berth panel, the said sheathings constituting aprons slightly projecting from the inner surface of the roof; 69, a curtain located back of the upper berth; 70, berth ropes which support the upper berth at the sides; 71, pulleys or friction wheels over which the ropes pass; 72, spring fusees to which the ends of the ropes are secured, said fusees being located in the alcoves so as not to prevent the closing of the upper berth against the wall of the car; 73, torsion braided wire mattresses or bed bottoms having the inner portions thereof attached to the inner or permanent parts of the lower berths; 74, the folding portions of the mattresses or bed bottoms; 75, berth guards secured to the outer edge of the movable part of the upper berth; 76, a guard rope or cord; 77, rings at the ends of the rope; 78, hooks secured to the arch rails; 79, the arch rails which may extend from one plate to the other or from one clear story sill to the other; 80, curtain rods in the arch rails; 81, posts, which extend from the seat backs to the arch rails; 82, a narrow head board which matches the edge of a bulkhead and engages at its outer edge one of the posts and closes the space between the top of a seat back and the end of an upper berth when lowered; 83, metallic pieces on the edge of the head board for engaging a post; 105, longitudinal plates of the car; 84, a removable cover for the alcove receptacle; 85, a rod support for one end of the top board or cover; 86, 87, leaves of a hinged door, the inner leaf being hinged to the wall of the car or to the bulkhead and seat back, and the other leaf hinged to the aforesaid leaf; 88, 89, alcove end doors, hinged to the seat backs or seat ends; 90, an opening to the space beneath a seat, formed by removing the lower portion of the seat back; 91, fold-

ing wash basins located, when folded, in or adjacent the car wall; 92, waste water pipes which discharge through the bottom of the car; 93, removable mattresses for the upper and lower berths which are stored in the alcove receptacles by day; 94, the ends of the seats; 95, in Fig. 8, the upper berth pivots which are fixed so as to have a rotary motion only; 96, a berth arm; 97, a guard; 98, a cord; 99 and 100 double torsion braided wire mattresses or bed bottoms—one part permanently attached in position and the other movable or hinged to the first mentioned part and adapted to fold; 101, a sliding rod frame movable relative to the inner or lower portion of the upper berth; 102, bearings within which the rods slide; 103, a curtain roll; and 104 the arch rails.

The substantial steps taken in reorganizing, reconstructing and arranging the interior of the car for the purposes specified consist in dividing up and apportioning the floor area, somewhat as shown in Figs. 1 and 2, so that the space along the side walls of the car will be divided into sections and each section be provided with an inclosed alcove adjacent its end; supporting upper berths which can contract or have one part movable relative to the other, provided with safety guards adjacent the central passage, and located above each sectional area shown in the plans; making parts of the cushions and back upholsterings of the seats within a section adjustable to form a lounge when so desired; and strengthening the top of the car with arch rails.

The sections are each made about 6' 1" long and of any convenient width. The backs of the seats of adjacent sections are spaced about 26" apart to form a washing and dressing alcove and a receptacle for bedding by day. Each cushion and back piece, exclusive of the head rest, is made in two pieces as shown. Under each cushion is attached a strip of wood having pins set therein which fit into holes in a permanent rail and which hold the cushions in place. The purpose of the strip at the front of the cushion is to raise the front edge so that a backwardly slanting seat will be formed. Each cushion has journals attached to its corners at the rear edge which move in the slotted plates, only one of said plates being shown. Each removable back piece is supported in proper position as shown in Fig. 7, by any suitable means. To form a lounge the front edge of each cushion adjacent the side of the car is raised far enough to withdraw the pins; each is then pulled forward to the position shown in dotted lines so as to rest upon the permanent rail; each removable back piece adjacent the wall is dropped to a horizontal position as indicated, the rear edge being supported on piece 64 and the front edge on ledge *l* attached to the cushion. By this

manipulation one half of the area is transformed into a lounge. A similar manipulation of the other half of the upholstering of the seats and backs transforms the whole 5 area into a foundation for a lower berth. The head rest may be made adjustable if desired in any well known way.

The upper berth is made in two parts, the inner or lower one comprising a wooden 10 panel with end pieces, said panel preferably being curved at the pivoted edge as shown in sectional view, Fig. 3, and the upper or outer portion having an edge piece or board and parts telescoping into the lower or inner part. 15 The particular manner in which the outer part of this upper berth contracts against the inner part or folds onto it is not material as various forms of mechanism may be selected. In the first example is shown the outer or 20 upper edge sliding between panels of the lower or inner part and the same constitutes a desirable construction. The torsion braided wire mattress or bed bottom is preferably made in two parts hinged together so it can 25 fold, the front part turning over onto the back part, which latter part may be fastened to the inner portion of the upper berth. The object is the provision of such a mattress or bed bottom as can be folded or shifted one 30 part relative to the other to allow the outer part 66 to be moved inwardly. When the berth is turned up the projection into the car from the wall will be only twice the thickness of the mattress or bed bottom, as shown at 35 the left in Fig. 3. A sheathing 68 is located on the ceiling above the plate so as to match the upper edge of the berth when folded against the wall. A cord and fusee, the latter placed in the alcove as shown, assist in 40 raising and lowering the berth. Friction pulleys may be used as bearings for the cords where they pass through the bulkheads. The upper berth is pivoted by fixed hinges or 45 pivotal means at its inner edge to the bulkheads, though it may be pivoted to the wall, and in such a manner that when lowered the body thereof lies in a plane below a horizontal plane through the pivots, and when raised lies substantially above the pivots. 50 This is an important feature, as it locates the berth by day as high from the floor as possible, allowing the use of relatively high windows and, when lowered for use by night, the berth is not too far from the floor to prevent 55 easy access thereto. The bulkheads are in line with the seat backs, preferably extend to the arch rails, and their inner edges abut the wall of the car, and they are of sufficient width to close up the ends of the 60 upper berth when the same is raised. A bulk-head forms in connection with the short head board 82 and a seat back one of the walls shutting off the lower berth at one end from an alcove. The short head board fits 65 a beading on the seat back and engages the

bulk head and has metallic clips engaging a post, as indicated at the right in Fig. 3. The curtain roll is located back of the upper berth at 69, but may be located below the pivoted inner edge of the upper berth as 70 shown at the right in Fig. 3. The location of the roll back of the berth allows the windows to extend several inches higher than otherwise.

To strengthen the car in the top and to 75 partially shut off one section and alcove from another, arch rails are located in line with the seat back boards and extend from plate to plate in the main example, and between the clear story sills in the modification 80 shown by Fig. 8. They may extend up to the ceiling of the clear story or be left open in that portion of the top of the car between the clear story sills. Posts 81 are located on the seat backs at their outer ends and join 85 the arch rails at their top ends. In the arch rails are located rods 80 which project through and terminate in hooks 78. To these hooks are secured the rings or eyes at the ends of the rope 76 which in part or entirely 90 support the upper berth in a horizontal position and entirely support the guard 75. This guard may be of any suitable material and may entirely shut off the upper berth space from the central passage, or it 95 may be of the form shown in Fig. 5 admitting access to the upper berth at the seat end. When extending the entire length of the berth access is had to the upper berth from the alcove only and it is thus made more desirable for sleeping purposes than the lower 100 berth.

It will be noted that the shape of the lower part of the upper berth panel is curved in cross section and that the pivots are located 105 near the extreme rear edge so that when the berth is closed up and in a raised position adjacent the plate, and extending a little above it, a graceful curve is presented which in connection with the sheathing above and upon the ceiling forms an ogee curve. Still further, and which is of much importance, the shape of the lower part of the berth and the location of the pivots allow the berth to lie when unfolded or swung down in a lower 110 plane than would be possible if the arrangement were otherwise. The distance from the top of the floor to the top of the plate is, for well known reasons, limited in practice to 6' 10" or 7'. The distance from the floor 120 over the seat cushions is about 1' 6". The distance between the berths should be approximately 3'. The construction and arrangement shown allows the upper berth to drop or swing to the desired position below 125 the top of the windows and also to take a high position above the window area in the day time, making the use of high windows possible, and to be substantially parallel with the side of the car and slightly project- 130

ing inwardly. When closed the upper berth is locked in position in any well known way as by the usual rods which are reciprocated by a handle 94' shown in Fig. 5.

5 The results of the method of construction set forth cannot be overestimated from a practical as well as from an artistic point of view, for the ponderous, inwardly and upwardly extending bunks of ordinary sleeping cars are entirely dispensed with and a means substituted which lies compactly adjacent the wall and plate of the car. However, the great advantages attending the improved construction of the upper berth make it 10 necessary to provide a storage receptacle for the mattresses, bedding, and other paraphernalia by day. The alcoves, therefore, are adapted to hold and conceal the bedding, &c., when not in use. The alcove construction is as follows: The lower part of the seat backs are cut away at 90° so the space under the seats can be utilized in connection with the alcove space proper. Two doors 88, 89 are hinged to the seat backs and fold inwardly as shown in dotted lines, Fig. 6. A 15 double door having leaves 86, 87 is hinged to the bulk head and swings, as shown in dotted line Fig. 6, to constitute a head board completely shutting off a section from an alcove 20 at one end. The cover for the alcove receptacle consists of a board of two leaves resting on top of the end doors and supported on rod 85 attached to door 86. The open space between the backs of the seats above the cover 25 is adapted for the reception of bundles, hand bags and the like during the day. There is shown in Fig. 6 one method of storing the bedding, 93, 93, being mattresses hung up or deposited behind the door 86 adjacent the 30 car wall. To economize space as much as possible a folding wash basin is arranged to close up into the car wall above a waste water discharge pipe. As shown in Fig. 5 the seat ends extend some distance beyond 35 the back boards making the entrance to the alcove narrower than the width of the alcove itself. The floors of the alcoves are substantially on a level with the car floor and the alcoves when adapted for use by passengers for undressing, dressing, and washing are inclosed except at their front portions. A free and unobstructed inclosed space and area is thus provided at the level of the floor for the purposes specified, the walls of an alcove, and especially the seat backs, serving 40 as supports for the passenger when equilibrium is disturbed by the swaying of the moving car. When a section is arranged for sleeping purposes the berth curtain is suspended from the rope 76 and rod 80 and shuts off both the section and the alcove 45 from the central passage of the car.

Fig. 8 illustrates a modified embodiment of the upper berth which consists in pivoting the arm 96 in the wall at 95, an arm being lo-

cated at each end, so that the berth will occupy a low position when swung down to a horizontal plane and a relatively high position adjacent the plate when raised or swung to a perpendicular position against the wall. 70 The mattress 100 is supported on a telescoping rod frame 101 movable in guides 102 located upon the paneled portion of the berth. The mattress folds to the position indicated by dotted lines and the outer edge of the rod frame is suspended and supported from the arch rail 104 by a guard 97 as shown. 75

While only one mode of the physical embodiments of the improvements, aside from the upper berth arrangement, has been set forth in full, it is not intended that the specific forms shall limit the scope of the invention. Other embodiments and forms may be used and many changes introduced without constituting substantial departures; for instance, the roof may be of a different shape; the upper berth contracted, adjusted, telescoped and transformed in a variety of equivalent ways; the elements which constitute the means for closing the alcove be modified in number, shape, and disposition; and many other and similar equivalents introduced. When the part substituted for any part herein shown or described is for the same purpose and made by taking substantially the same steps as the part it replaces, it will be regarded as falling within the scope of my invention. 95

What I claim as new and desire to secure by Letters Patent is:

1. The combination in a car, of two seats facing each other, each seat having a cushion and movable back upholstering; grooved plates suitably supported; and journals carried by the seat cushion and located in the grooves of the plates. 100
2. The combination in a car, of two seats facing each other, each seat having two cushions and movable back upholstering made in two parts; grooved plates suitably supported; and journals carried by the seat cushions and located in the grooves of the plates. 110
3. The combination in a car, of two seats facing each other, each seat having a cushion and movable back upholstering; grooved plates; journals carried by the seat cushion and located in the grooves of the plates; and removable means located at the front edges of the cushions for raising the edges and causing the cushions to slant rearwardly. 115
4. The combination in a car, of two seats facing each other, each seat having two cushions and movable back upholstering in two parts; grooved plates; journals carried by the cushions and located in the grooves of the plates; and movable means at the front under surfaces of the cushions for raising the outer edges of the same. 120
5. The combination in a car, of two seats facing each other, each seat having a cushion 130

with a strip, as 62, secured to its under surface and said strip provided with a pin or pins, as 63; and a seat rail with a hole or holes for the pin or pins.

5. The combination in a car, of two seats facing each other, each seat having two cushions and movable back upholstering made in two parts; means at the under and outer edges of the cushions for raising said outer edges; and means for supporting and guiding the rear edges of the cushions so each separately may be drawn outwardly and supported on a seat rail.

7. The combination in a car, of two seats facing each other, each seat having two cushions and back upholstering made in two parts; means for supporting the cushions when drawn out; and means carried by each cushion, as a ledge, to support the front edge 20 of one part of the back upholstering when lowered.

8. The combination in a car, of two seats facing each other, each seat having two cushions and movable back upholstering made in two parts; means at the outer and under surface of each cushion for raising its outer edge so the seat will slant rearwardly; and means for supporting two cushions and two parts of the back upholsterings in a horizontal plane 30 to form a sofa; the remaining cushions and back upholsterings being retained in their normal positions.

9. The combination in a car, of two seats facing each other, each seat having two cushions and movable back upholstering made in two parts; permanent seat rails, as 61; and means for supporting two cushions and two parts of the back upholsterings in a horizontal plane to form a sofa comprising part only 40 of the area between the seat backs; the said cushions when drawn out so their edges will meet being supported by the seat rails.

10. The combination in a car, of two seats facing each other, each seat having a cushion 45 and movable back upholstering; and means at the rear edge of the cushion for supporting and guiding the same when drawn out and resting upon the seat rail.

11. The combination with a car, of an upper berth comprising inner and outer parts, said inner part consisting of a panel with end pieces, and said outer part movable away from and towards the inner part for widening and contracting the berth; the inner part being pivoted or hinged at its extreme rear edge or portion to the car so that when swung up the body of the berth will be above the pivotal points, and when lowered the body of the berth will lie in a horizontal plane below 55 the pivotal points.

12. The combination with a car, of an upper berth comprising inner and outer parts, said inner part consisting of a panel curved in cross section at its inner edge portion, and 65 said outer part movable away from and to-

wards the inner part for widening and contracting the berth, the inner part being pivoted or hinged at its extreme curved rear edge or portion to the car, whereby the pivotal points are above the berth when lowered and 70 below the body thereof when the berth is turned up.

13. The combination with a car, of an upper berth comprising inner and outer parts, said inner part consisting of an outer panel 75 and an inner panel spaced apart, and said outer part of the berth having a part or parts thereof located between the said two panels of the inner part and movable away from and towards the inner part for widening and contracting the berth, the said inner part being pivoted at its extreme rear edge or portion to the car.

14. The combination with a car wall, of an upper berth comprising inner and outer parts, 85 said inner part consisting of a panel, and said outer part movable away from and towards the inner part for widening and contracting the berth, the inner part being pivoted or hinged at its rear edge to the car, and said 90 berth when contracted and turned to a vertical position having its free edge located adjacent the inner surface of the roof, whereby space is provided below the berth for relatively high windows.

15. The combination with a car wall, of an upper berth comprising inner and outer parts, said inner part consisting of a panel, and said outer part movable away from and towards the inner part for widening and contracting the berth, the inner part being pivoted or hinged at its rear edge to the car, and said 100 berth when contracted and turned to a vertical position having its free edge located adjacent the inner surface of the roof; and a 105 sheathing or apron located upon the inner surface of the roof adjacent the edge of the berth.

16. The combination with a car wall and vertical bulk-heads, of an upper berth having an inner part comprising a panel and end pieces, and an outer part movable relative to the inner part; said inner part of the berth being pivoted to the car at its rear edge, and its outer surface when said berth is contracted and raised to a vertical position lying in line with the edges of the said bulk-heads, whereby the ends of the berth will be covered by the bulk-heads.

17. The combination with a car, of an upper berth comprising inner and outer parts, said inner part consisting of a panel with strengthening end pieces, and said outer part movable away from and towards the inner part for widening and contracting the berth, the inner part being pivoted or hinged at its rear edge to the car; and means for supporting the outer edge of said outer part when the same is moved away from the inner part and adapted for use.

18. The combination with a car wall, of an upper berth comprising inner and outer parts, said inner part consisting of a panel with strengthening end pieces, and said outer part 5 movable away from and towards the inner part for widening and contracting the berth; the inner part being pivoted or hinged at its extreme rear edge to the car by fixed pivots so located that when the berth is contracted 10 and swung up the body thereof will be above the pivotal points and when lowered and extended the body of the berth will lie below the pivotal points; and means for supporting the outer edge of the outer part of the berth 15 when moved away from the inner part.

19. The combination with a car, of an upper berth comprising an inner part and an outer part, said inner part consisting of a panel, and said outer part movable away 20 from and towards the inner part, said inner part being pivoted or hinged at its inner edge to the car; and a guard in connection with the outer edge of the said outer part and supported at the roof to prevent the occupant 25 from being thrown from the berth.

20. The combination with a car, of two vertical bulkheads, as 54, secured in position against the car wall; and a contracting upper berth pivoted to the car and adapted to occupy 30 a vertical position between the two bulkheads and adjacent the roof and wall of the car, and also adapted to rotate on the pivots to a horizontal position with the body of the berth below the pivots; and means for 35 supporting the outer edge of the berth when extended.

21. The combination with a car having windows, of the two seat backs 55; the two bulkheads 54 in line with the seat backs; an 40 upper berth having an inner panel pivoted at its rear edge to the car, and an outer part movable away from and towards the inner panel; said upper berth when contracted being adapted to occupy a vertical position between the bulkheads and above the windows 45 and with its top edge adjacent the roof and to rotate on its pivots to a horizontal position below the pivots.

22. The combination with a car, of the 50 seat backs 55; the bulkheads 54; a collapsible upper berth pivoted to the car at its inner edge and adapted to occupy a vertical position between the bulkheads; arch rails in line with the seat backs and bulkheads; and 55 means for supporting the outer edge of the berth from the arch rails when in a horizontal position and extended.

23. The combination with a car, of seat backs 55; bulkheads 54; an alcove adjacent 60 the seat back; a contracting upper berth adapted to occupy a vertical position between the bulkheads; a fusee located in the alcove; and a cord or chain secured to the berth and fusee.

65 24. The combination with a car, of seat

backs 55; bulkheads 54; alcoves; a pivoted upper berth; two fusees located within the alcoves; two bearings; and cords or chains secured to the berth and fusees and passed over the bearings.

70 25. The combination with a car, of an upper berth comprising inner and outer parts, the inner part consisting of a panel pivoted or hinged at its inner edge to the car, and said outer part movable away from and towards the inner part for widening and contracting the berth; and a mattress or bed bottom part of which can be turned over or shifted upon the other part, thus allowing the said outer part of the berth to be moved 75 towards the inner part and the entire berth 80 to be turned to a substantially vertical position adjacent the car wall.

85 26. The combination with a car, of an upper berth comprising inner and outer parts, the inner part consisting of a panel pivoted or hinged at its inner edge to the car, and said outer part movable away from and towards the inner part for widening and contracting the berth; and a mattress or bed 90 bottom formed of a plurality of pieces one of which can be turned or shifted upon the other, allowing the said outer part of the berth to be moved towards the inner part, and the berth to be turned to a vertical position 95 adjacent the wall so as to project into the car interior a distance equal only to twice the thickness of the mattress or bed bottom.

27. The combination with a car, of an upper berth comprising two parts one of which 100 is pivoted or hinged to the car at its inner edge, and the other part movable towards and away from the first part; and a folding mattress or bed bottom.

105 28. The combination with a car, of an upper berth comprising a plurality of parts, the inner part being pivoted or hinged at its inner edge to the car, and the outer part movable towards and away from the inner part; and a mattress or bed bottom the front part 110 of which can be turned over upon the rear part, thus allowing the entire berth to be extended and also contracted so as to occupy when turned up a substantially vertical position below the roof of the car.

115 29. The combination with a car, of a berth comprising two parts, one a panel with end pieces, and the other having an edge piece and bodily movable towards and away from the panel; and a mattress or bed bottom 120 comprised of a plurality of pieces one of which can be shifted or turned on the other; the said panel being hinged or pivoted to the car and the entire berth and bed bottom when contracted adapted to occupy a substantially vertical position adjacent the car wall and roof.

125 30. The combination with a car, of an upper berth hinged or pivoted to the car and comprising two parts, one of which slides 130

relative to the other, and a folding mattress or bed bottom.

31. The combination with a car, of an upper berth hinged or pivoted to the car and comprising two parts, one of which slides relative to the other; a folding mattress or bed bottom; and means for supporting the outer edge of the berth and bed bottom when the same are extended for use.

10 32. The combination in a car, of a series of sections and alcoves located along the opposite sides thereof; and arch rails located in the top of the car and substantially in line with the seat backs which bound the alcoves and the sections.

33. The combination in an alcove sleeping car, of the seat backs; bulkheads; and arch rails; the same being located substantially in vertical planes for bounding and partially separating alcoves from sections.

20 34. The combination in an alcove sleeping car, of seat backs 55; bulkheads 54; and arch rails extending in line with the seat backs below the clear story sills.

25 35. The combination in an alcove sleeping car, of the seat backs; alcoves between seat backs; bulkheads; arch rails; folding upper berths adapted to occupy positions between the bulkheads; and means supporting the berths when lowered.

35 36. The combination in an alcove sleeping car, of the seat backs; bulkheads; arch rails substantially in the top of the car in line with the seat backs and bulkheads; and contracting upper berths which fold to vertical positions.

37. The combination in an alcove sleeping car, of the seat backs; bulkheads; arch rails substantially in line with the bulkheads and 40 seat backs; folding upper berths adapted to occupy vertical positions between the bulkheads; and means for supporting the berths when lowered to horizontal positions.

38. The combination in an alcove sleeping 45 car, of seat backs, bulkheads, and arch rails, the same being located substantially in vertical planes and constituting the boundaries of alcoves and sections; and posts extending from the seat backs to the arch rails.

50 39. The combination in an alcove sleeping car, of seat backs, bulkheads, and arch rails, the same being located substantially in vertical planes and constituting the boundaries of alcoves and sections; and movable head 55 boards for shutting off the alcoves from the sections or spaces occupied by the seats.

40. The combination in an alcove sleeping car, of seat backs, and bulkheads, the same being located in vertical planes and spaced 60 to form alcoves and sections; folding upper berths adapted to occupy horizontal positions; and movable partitions or headboards, one type consisting of hinged partitions and the other type closing the opening between

the top edge of a seat back and the end of 65 an upper berth when lowered, whereby access may be had to the upper berth end from an alcove.

41. The combination in an alcove sleeping car, of seat backs and bulkheads bounding 70 the alcoves and sections; and movable partitions being hinged to the car and one of said partitions consisting of a plurality of folding leaves.

42. The combination in an alcove sleeping 75 car, of seat backs and bulkheads bounding the alcoves and sections; and movable partitions; one of which for an alcove has two leaves and is hinged to the surface of a bulkhead and extends below the seat back, the 80 wider leaf being of the width of an alcove and forming when closed the door of a closet bounded by the car wall and bulkheads.

43. The combination in an alcove sleeping car, of seat backs and bulkheads bounding 85 the alcoves and sections; movable means, as doors 88, 89, for closing the ends of the alcoves; and movable top covers, as 84, each located in a horizontal plane below the tops of the seat backs.

44. The combination in an alcove sleeping car, of seat backs and bulkheads bounding the alcoves and sections; means for closing the end of each alcove; a cover located in a plane below the tops of the seat backs of each 95 alcove; and movable means for closing the space between the bulkheads and car wall to form a closet in each alcove.

45. The combination in an alcove sleeping car, of seat backs shutting off sections from 100 alcoves and bulkheads bounding the alcoves and sections; means for closing the end of each alcove; a cover for each alcove located below the tops of the seat backs; and a swinging door extending below the seat 105 backs, serving to shut off the alcove from one section by night and as a door to a closet by day.

46. The combination in a sleeping car, of fixed seat backs located adjacent the car 110 walls and at right angles thereto dividing the floor area into a central aisle, sections, and alcoves; seats and upholsterings adapted to form a lower berth in each section; means for entirely closing one side of each alcove; a movable wall at the front of an alcove and a movable top piece located in an alcove below the tops of the seat backs to form a receptacle for bedding and also a space for hand baggage above the movable top piece by day; 120 and a contracting upper berth hinged to the car in each section and adapted to swing to a vertical position adjacent the wall.

47. In a sleeping car, the combination with the bulkheads and seat backs, of hinged 125 and folding headboards, each consisting of two parts 86 and 87, in substance as set forth.

48. The combination in a sleeping car, of a

seat back; a bulkhead; an arch rail; and a hinged and swinging head board for entirely shutting off an alcove from a section.

49. In a sleeping car, the combination with the arch rails, of the rods and means, as hooks 78, for supporting the upper berth at its outer edge and also the guard of the upper berth.

50. The combination in a car, of pairs of seats facing each other; alcoves between seat backs; bulkheads; pivoted and contracting upper berths, each located between two bulkheads when folded; arch rails substantially in line with the seat backs; and posts extending from the arch rails to the seat backs.

51. The combination in a sleeping car, of fixed seat backs located adjacent the car wall and at right angles thereto dividing the floor area into a section and an alcove; an upper berth in the section comprised of inner and outer parts, said inner part consisting of a panel pivoted or hinged at its inner edge to the car, and said outer part movable away from and towards the inner section for widening and contracting the berth; said berth when contracted being adapted to swing up to a vertical position close against the car wall; and movable means for inclosing part of the alcove space to form a receptacle by day for the bedding of the upper berth.

52. The combination in a sleeping car and with a pair of windows, of a collapsible upper berth which when raised occupies a substantially vertical position above the windows and when turned downwardly occupies a lower position in a horizontal plane below or adjacent the upper edge of the windows; an alcove adjacent a seat back; and means for inclosing the alcove thus forming a receptacle to receive the bedding by day.

53. A sleeping car having pairs of seats facing each other and adapted to be transformed into lower berths; collapsible upper berths; hinged movable partitions, extending from the seat backs to positions above the upper berths when lowered; alcoves adjacent the seat backs; and head boards, as 82, for shutting off the alcoves from the lower berths.

54. The combination in a sleeping car, of fixed seat backs located adjacent the car wall and at right angles thereto dividing the floor area into a section and an alcove; means for forming a lower berth in the section; a contracting upper berth hinged to the car in the section and adapted when contracted to swing up to a vertical position against the wall; partitions closing the section at one end and the alcove at one side; and movable means for inclosing part of the alcove to form a receptacle for the bedding of the berths by day.

55. The combination in an alcove sleeping

car, of the seat backs 55; bulkheads 54; a folding wash basin, as 51, located adjacent the car wall; and a door hinged to a bulkhead which serves to conceal the basin when folded, and also by night serves to shut off an alcove from adjacent upper and lower berths.

56. The combination in an alcove sleeping car of the seat backs 55; bulkheads 54; a folding wash basin adjacent the car wall; and movable means in connection with the bulkheads forming a partition which conceals the basin when folded.

57. The combination in an alcove sleeping car, of two seat backs bounding an alcove; removable means for closing the end of the alcove; a removable cover below the tops of the seat backs; and a folding partition having means, as a rod 85, to support the end of the removable cover.

58. The combination in an alcove sleeping car of seat backs 55 bounding an alcove and cut away at 90; means for closing the end of the alcove; and a removable cover located below the tops of the seat backs.

59. The combination in an alcove sleeping car, of seat backs bounding alcoves; seats arranged in pairs; bulk-heads in line with the seat backs; upper berths located when folded between the bulk-heads; movable means for closing the spaces between bulk-heads to form pockets or receptacles; and movable partitions or head boards in connection with the seat backs which latter entirely shut off each alcove from the adjacent lower berths, said alcoves being unobstructed for use as specified.

60. The combination in an alcove sleeping car, of pairs of seats facing each other; seat backs 55, 55 spaced apart to form alcoves between said seat backs; and seat ends 94, 94, which extend beyond the backs 55 and in front of the alcove spaces.

61. The combination in a sleeping car, of permanent seat backs and bulk heads arranged at right angles to the wall thereof and forming a plurality of sections and alcoves, said bulk heads being substantially in the planes of the seat backs and located adjacent the ends of the upper berths when folded; and movable means for inclosing the space between two adjacent bulk heads and the car wall to form an openable cabinet; the alcoves being shut off from the lower berths by the permanent seat backs, and open and unobstructed sufficiently to afford suitable standing space for passengers in undressing and dressing.

62. The combination in a sleeping car, of permanent seat backs and bulk heads arranged at right angles to the wall thereof and forming a plurality of sections and alcoves, said bulk heads being substantially in the planes of the seat backs and extending up-

wardly therefrom and located adjacent the ends of the upper berths when folded; and movable means for inclosing the space between two adjacent seat backs, two bulk 5 heads and the wall of the car to form an openable cabinet, the alcoves being shut off from the lower berths by the seat backs, and open and unobstructed sufficiently to afford suitable secluded standing space for 10 passengers in undressing and dressing.

63. The combination in a sleeping car, of permanent seat backs and bulk heads arranged at right angles to the wall thereof and forming a plurality of sections and alcoves, 15 said bulk heads being substantially in the planes of the seat backs and located adjacent the ends of the upper berths when folded; movable means for inclosing the space between two adjacent bulk heads and the car 20 wall to form an openable cabinet; and a wash basin within the cabinet; the alcoves being shut off from the lower berths by the permanent seat backs.

64. The combination in a sleeping car, of permanent seat backs and bulk heads arranged at right angles to the wall thereof and forming a plurality of sections and alcoves, 25 said bulk heads being substantially in the planes of the seat backs, extending upwardly 30 and located adjacent the ends of the upper berths when folded; movable means for inclosing space between two adjacent bulk heads and the car wall to form an openable cabinet; and a folding wash basin within the 35 cabinet; the alcoves being shut off from the lower berths by the seat backs.

65. The combination in a sleeping car of permanent seat backs and bulk heads arranged at right angles to the wall of the car 40 and forming a plurality of sections and alcoves, said bulk heads being substantially in the planes of the seat backs and located adjacent the ends of the upper berths when folded; movable means for inclosing the 45 space between two adjacent bulk heads and the car wall to form an openable cabinet; and a movable, horizontally disposed platform crossing the space between the seat backs and located below the tops of said seat 50 backs, said alcoves being open and unobstructed sufficiently to afford suitable secluded standing spaces for passengers in undressing and dressing.

66. The combination in a sleeping car, of three fixed seat backs 55 in series located adjacent the car wall and at right angles thereto dividing the floor area into a section 1 and an alcove space 2 adjacent the wall; seats with upholsterings movable to form a lower 60 berth within the section; means for forming a horizontal upper berth above the seats and entirely within the section; and two head boards or partitions, one of them being movable, in connection with the seat back at one 65 side of the alcove and the seat back at the

end of the section remote from the alcove for inclosing said section and alcove; said alcove space being open and unobstructed above the floor providing free standing room for the passenger in undressing and dressing, and 70 said alcove space also entirely shut off from the lower berth of the section by the fixed seat back so access to the lower berth is possible only by way of the front of the section.

67. The combination in a sleeping car, of three fixed seat backs 55 in series located adjacent the car wall and at right angles thereto dividing the floor area into a section 1 and an alcove space 2 adjacent the wall; seats with upholsterings movable to form a lower 80 berth within the section; means for forming a horizontal upper berth above the seats and entirely within the section; a wash basin at the wall in the alcove; and two head boards or partitions, one of them being movable, in 85 connection with the seat back at one side of the alcove and the seat back at the end of the section remote from the alcove for inclosing said section and alcove; said alcove space being open and unobstructed above the floor 90 providing free standing room for the passenger in undressing, washing and dressing, and said alcove space also entirely shut off from the lower berth of the section by the fixed seat back so access to the lower berth 95 is possible only by way of the front of the section.

68. The combination in a sleeping car, of three fixed seat backs 55 in series located adjacent the car wall and at right angles thereto dividing the floor area into a section 1 and an alcove space 2 adjacent the wall; seats with upholsterings movable to form a lower berth within the section; means for forming a horizontal upper berth above the seats and entirely within the section; two head boards or partitions, one of them being movable, in connection with the seat back at one side of the alcove and the seat back at the end of the section remote from the alcove for inclosing 100 said section and alcove; said alcove space being open and unobstructed above the floor 105 providing free standing room for the passenger in undressing and dressing, and said alcove space also entirely shut off from the lower berth of the section by the fixed seat back so access to the lower berth is possible 110 only by way of the front of the section; and movable partitions for closing part of the alcove space between the seat backs, or at the 115 rear of the seat back, to form a receptacle by day.

69. The combination in a sleeping car, of fixed seat backs located adjacent the car walls and at right angles thereto dividing the 120 floor area into a central aisle, sections, and alcove spaces adjacent the walls; seats with upholsterings movable to form lower berths in the sections; and means for forming a horizontal upper berth directly above the 130

seats in each section and entirely within the same; said alcoves being open and unobstructed above the floor providing free standing spaces for passengers in undressing and 5 dressing, and each alcove space also entirely shut off from the lower berth or berths by the fixed seat back or fixed seat backs so access to said lower berths is possible only by way of the central aisle.

10 70. The combination in a sleeping car, of fixed partitions and seat backs located adjacent the car walls and at right angles there-to dividing the floor area into a central aisle, sections, and alcove spaces adjacent the 15 walls; seats with upholsterings movable to form lower berths in the sections; means for forming a horizontal upper berth directly above the seats in each section and entirely within the same; and a wash basin adjacent 20 the wall in each alcove; said alcoves being open and unobstructed above the floor providing free standing spaces for passengers in undressing, dressing and washing, and each alcove space also entirely shut off from the 25 lower berth or berths by the fixed seat back or fixed seat backs so access to said lower

berths is possible only by way of the central aisle.

71. The combination in a sleeping car, of fixed partitions and seat backs located adjacent the car walls and at right angles there-to dividing the floor area into a central aisle, sections, and alcove spaces adjacent the 30 walls; seats with upholsterings movable to form lower berths in the sections; means for 35 forming a horizontal upper berth directly above the seats in each section and entirely within the same; and movable head boards or partitions in connection with the seat backs; said alcoves being open and unob- 40 structed above the floor providing free standing spaces for passengers in undressing and dressing, and each alcove space also entirely shut off from the lower berth or berths by the fixed seat back or fixed seat backs so access 45 to said lower berths is possible only by way of the central aisle.
